UNITED STATES PATENT OFFICE.

GARTH G. GILPIN, OF RIVERSIDE, ILLINOIS.

UNCOUPLING DEVICE FOR CAR COUPLERS.

Continuation of application Serial No. 458,501, filed April 4, 1921. This application filed December 14, 1922, Serial No. 606,871. Renewed February 9, 1924.

To all whom it may concern:

Be it known that I, GARTH G. GILPIN, a citizen of the United States, residing at Riverside, in the county of Cook and State 5 of Illinois, have invented new and useful Improvements in Uncoupling Devices for Car Couplers, and more particularly to devices of this character employed on freight cars and frequently known as release rig- 10 gings.

It is the object of this invention to provide a simple and efficient release rigging comprising but few parts and which can be readily attached to the different types of 15 freight cars.

This particular invention relates to what is generally known in this art as the push down type of uncoupling device and comprises two levers having their adjacent ends 20 pivotally mounted on the same fulcrum. The particular advantage of this construction resides in the manner in which the levers are pivoted upon the fulcrum. In 25 levers of this general type mounted on a common fulcrum the connection between the levers must allow for the longitudinal movement of the coupler head in draft and in buffing and the rotative movement of the pin lifting lever about the fulcrum must be 30 limited for the purpose of safety to the operator.

The manner of mounting the levers on the fulcrum, in accordance with this invention, provides at the fulcrum means allowing 35 play of the free end of the pin lifting lever in a horizontal plane without transmitting such movement to the hand lever.

In the drawings:

Fig. 1 is a view in end elevation of a portion 40 of a freight car illustrating the application of this invention.

Fig. 2 is a top plan view of the same.

Fig. 3 is an enlarged detail top plan view 45 of the fulcrum and adjacent ends of the levers with parts broken away.

Fig. 4 is an enlarged view in end elevation of Fig. 3.

Fig. 5 is a view in section taken on the line 5—5 of Fig. 3 looking in the direction 50 of the arrows.

Fig. 6 is a perspective view of the fulcrum.

Fig. 7 is a perspective view of the combined connecting and bearing block.

Fig. 8 is a perspective view of the washer. 55

Fig. 9 is a perspective view of the nut.

Fig. 10 is a perspective view of the fulcrum end of the operating lever.

Fig. 11 is a perspective view of the fulcrum end of the pin lever. 60

In the embodiment of this invention as illustrated the numeral 1 indicates the end of a freight car of the non-end sill type; 2 the striking casting; 3 the coupler head; 4 the coupler locking pin eye; 5 the side sill 65 and 6 the brake mast, all of which are of usual construction.

The uncoupling device comprises an operating lever 7 and a pin lifting lever 8 having their adjacent ends mounted on a common fulcrum including a casting 9 mounted on a plate 10 depending from the underside of the car end. The pin lifting lever is provided with an offset to pass the brake mast with its free end portion parallel to the car end, and is of reduced size, to pass through and beyond the eye of the locking pin with the extremity bent in the form of a hook. Both ends of both levers are preferably offset, as shown, so that their extremities will lie in parallel horizontal planes which will allow the coupler head to move back and forth transversely without transmitting its movement to the pin lifting lever, provide a more convenient manner for 80 attaching and mounting the adjacent ends of the levers on the fulcrum and afford a ready hand grip or foot engagement on the free end of the operating lever. 85

The fulcrum casting 9 comprises a base 90 plate having a hollow boss 11 extending at right angles therefrom and is provided with a reduced cylindrical portion 12 at its outer end. Rectangular openings 13 are swedged in the adjacent ends of the operating and 95 pin lifting levers through which is passed a rectangular connecting and bearing block 14 having a central aperture adapted to pass over and rotate upon the reduced portion 12 of the fulcrum casting, thus the connecting 100

and bearing block forms rotative connection between the levers and the fulcrum and furthermore the rectangular openings in the two levers co-act with the rectangular perimeter of the block, whereby the levers have a non-rotative connection therewith so that the two levers have a unitary vertical movement. This connecting and bearing block 14 is provided on the outside along its upper and lower edges with right angular lugs or projections 15 and the block is secured in position by a bolt 16 passing from the rear through the supporting plate 10 and parts 11 and 12 of the fulcrum casting having a washer 17 and nut 18 on the outer end of the fulcrum adapted to be engaged by the outer side of the bearing block. It is preferable to arrange the hand operating lever on the inner side adjacent to the shoulder formed by the part 11. To allow or compensate for longitudinal movement of the free end of the pin lifting lever, the end of this lever about the fulcrum is bent at an angle, as clearly shown in Fig. 3, so that the bend 19 in the metal is vertical and passes through the center of the fulcrum. The lugs or projections 15 on the connecting bearing block may be tapered from the center of the fulcrum towards each end. However, the thickest portion will be opposite the bend in the pin lifting lever so that movement back and forth in the direction of the longitudinal center of the car will cause this end of the lever to pivot on the bearing block projections without transmitting such movement to the operating lever. Since the bearing and connecting block is of rectangular shape and is received within similar rectangular openings in the ends of each of the levers a downward movement of the operating lever will cause a corresponding upward movement to the pin lifting lever for unlocking the coupler head.

While this invention is illustrated as applied to a certain type of freight car, it is readily adapted with but slight immaterial changes for application to other types.

This application is a continuation of my application Serial No. 458,501, filed April 4, 1921; certain typical forms of the invention herein disclosed being originally shown and described in said application.

What I claim is:

1. A release rigging for railroad car couplers comprising an operating lever, a coupler lock pin lifting lever, a fulcrum for said levers upon the car, and a combined connecting and bearing block which passes through apertures in said levers.
2. A release rigging for railroad car couplers comprising an operating lever, a coupler lock pin lifting lever, a fulcrum for said levers upon the car, a combined connecting and bearing block which passes
- 65

through apertures in said levers, and means thereon allowing pivotal movement of the pin lifting lever thereon horizontally independent of the operating lever.

3. A release rigging for railroad car couplers comprising an operating lever, a coupler lock pin lifting lever, a fulcrum for said levers upon the car, and a combined connecting and bearing block for said levers upon said fulcrum passing through the adjacent ends of said levers.

4. A release rigging for railroad car couplers comprising an operating lever, a coupler lock pin lifting lever, a shouldered fulcrum for said levers upon the car, a combined connecting and bearing block for said levers upon said fulcrum, and means thereon retaining the levers thereon between said means and the fulcrum shoulder.

5. A release rigging for railroad car couplers comprising an operating lever, a coupler lock pin lifting lever, a fulcrum for said levers upon the car, a combined connecting and bearing block of rectangular contour upon said fulcrum passing through similarly shaped apertures provided therefor in the adjacent ends of said levers, and means for retaining said block upon said fulcrum.

6. A release rigging for railroad car couplers comprising an operating lever, a coupler lock pin lifting lever, a fulcrum for said levers upon the car, a combined connecting and bearing block for said levers upon said fulcrum, and lugs upon the upper and lower sides thereof adapted to hold said levers thereon.

7. A release rigging for railroad car couplers comprising an operating lever, a coupler lock pin lifting lever, a fulcrum for said levers upon the car, a combined connecting and bearing block for said levers upon said fulcrum passing through apertures provided in the adjacent ends of said levers, lugs upon the upper and lower edges of said block adapted to hold said levers thereon, said apertured end of the pin lifting lever having a bend therein, and said lugs tapered from center to ends co-acting with said bent portion of the pin lifting lever to allow limited pivotal movement on said block about said lugs.

8. In a release rigging for car couplers comprising an operating lever having an aperture adjacent its fulcrum end, a coupler pin lifting lever having an aperture adjacent its fulcrum end, a member passing through said apertures having non-rotative connection therewith, and a fulcrum passing through said member having a rotative connection therewith, said levers mounted upon said member so as to permit relative horizontal movement between said levers.

9. In a release rigging for car couplers comprising an operating lever having an

aperture adjacent its fulcrum end, a coupler pin lifting lever having an aperture adjacent its fulcrum end, a member passing through said apertures having a non-rotative connection therewith, and a fulcrum passing through said member having a rotative connection therewith.

10. An article of manufacture for uncoupling devices for car couplers, a combined connecting member and bearing block having a rectangular perimeter and a circular interior bearing.

GARTH G. GILPIN.
